Primary Examiner — Paula Greene(74) *Attorney, Agent, or Firm* — Burr & Brown, PLLC(57) **CLAIM**

The ornamental design for a headphone, as shown and described.

DESCRIPTION

FIG. 1 is a front view of a headphone illustrating my new design;

FIG. 2 is a rear view thereof;

FIG. 3 is a right side view thereof;

FIG. 4 is a left side view thereof;

FIG. 5 is a top view thereof;

FIG. 6 is a bottom view thereof; and,

FIG. 7 is a perspective view thereof, the opposite interior front face of the headphone ear cup is the same.
